UNITED STATES PATENT OFFICE.

GEORGIANA A. BUCKLEY, OF MONTROSE, COLORADO.

PIN-TICKET.

1,148,659.

Specification of Letters Patent. Patented Aug. 3, 1915.

Application filed April 29, 1914. Serial No. 835,828.

To all whom it may concern:

Be it known that I, GEORGIANA A. BUCKLEY, a citizen of the United States, residing at Montrose, in the county of Montrose and 5 State of Colorado, have invented certain new and useful Improvements in Pin-Tickets, of which the following is a specification, reference being had to the accompanying drawings.

10 This invention relates to certain improvements in pin tickets and has relation more particularly to a device of this general character especially designed and adapted for use in connection with articles of merchandise; and the object of the invention is to provide a pin ticket of this general character having novel and improved means whereby the possibility of injury being caused by the prongs of the ticket before 15 and after being applied to the articles of merchandise is substantially entirely eliminated.

20

The invention consists in the details of construction and in the combination and arrangement of the several parts of my improved pin ticket whereby certain important advantages are attained and the device is rendered simpler, less expensive and otherwise more convenient and advantageous for 25 use, all as will be hereinafter more fully set forth.

The novel features of the invention will be carefully defined in the appended claim.

In order that my invention may be the 30 better understood, I will now proceed to describe the same with reference to the accompanying drawings, wherein—

Figure 1 is a plan view of a pin ticket constructed in accordance with an embodiment of my invention, with the prongs thereof in their initial or inoperative position; Fig. 2 is a plan view of my improved pin ticket as herein set forth, with the prongs adjusted into a position to penetrate 35 an article of merchandise; Fig. 3 is a plan view illustrating my improved pin ticket as herein set forth, with the prongs adjusted into locking position, the coacting fabric being shown in fragment; Fig. 4 is a view in side elevation of my improved pin ticket as disclosed in Fig. 3; and Fig. 5 is a longitudinal sectional view taken through my improved ticket as disclosed in Fig. 1, with the coacting pin shown in elevation.

50 As herein embodied, I provide a strand

of wire which is bent intermediate its length to afford the substantially parallel prongs 1, with the intermediate or headed portion 2 at its junctions with the prongs 1 bent to afford the loops 3 adapted to afford pockets 60 in which the free extremities of the prongs 1 are adapted to be depressed after the prongs 1 have been properly directed through an article of merchandise.

The ticket 4 in predetermined proximity 65 to one of its ends is provided with a transversely disposed offset 5 through which the prongs 1 are projected, with the prongs 1 and intermediate portion 2 initially disposed in substantial parallelism with the 70 opposite faces of the ticket 4 whereby it will be perceived that in handling the pin ticket, the possibility of injury from the prongs 1 is substantially entirely eliminated. When it is desired to apply the pin ticket 75 to an article of merchandise, the headed or intermediate portion 2 is manipulated in a convenient manner so as to cause the prongs 1 to assume the position particularly illustrated in Fig. 2, and after the prongs have 80 been disposed through the article of merchandise, the free extremities of the prongs are bent back upon themselves with their extremities depressed within the pockets afforded by the loops 3, as is particularly 85 shown in Figs. 3 and 4, and whereby persons handling an article of merchandise are prevented from being injured by the prongs, as is believed to be clearly apparent to those skilled in the art to which my present invention appertains.

From the foregoing description, it is thought to be obvious that a pin ticket constructed in accordance with my invention is of an extremely simple and comparatively 95 inexpensive nature and is particularly well adapted for use by reason of the convenience and facility with which it may be assembled, and it will also be obvious that my invention is susceptible of some change and 100 modification without material departure from the principles and spirit thereof and for this reason I do not wish to be understood as limiting myself to the precise arrangement and formation of the several 105 parts herein shown in carrying out my invention in practice.

I claim:

A device of the character described including a pin ticket provided with an off- 110

set portion intermediate its length, and a wire pin comprising a pair of prongs and an intermediate portion connecting said prongs, said prongs being disposed through the offset portion of the ticket and initially lying in substantial parallelism with the opposite faces of the ticket, the intermediate portion of the pin at its junctions with the prongs being bent to form outwardly dis-

posed loops to receive the free extremities of 10 the prongs.

In testimony whereof I affix my signature in the presence of two witnesses.

GEORGIANA A. BUCKLEY.

Witnesses:

MARGARET STERCHI,
ERIC CRUNSTEDE.
